DESIGN FOR A HOLDER FOR JELLIES OR THE LIKE

Helen Bishop Dennis, New York, N. Y., assignor to The Chase Companies, Incorporated, Waterbury, Conn., a corporation

Application September 6, 1935, Serial No. 58,456

Term of patent 7 years

To all whom it may concern:

Be it known that I, Helen Bishop Dennis, a citizen of the United States, residing at New York city, in the county of New York and State of New York, have invented a new, original, and ornamental Design for a Holder for Jellies or the like, of which the following is a specification, reference being had to the accompanying drawing, forming part thereof.

Fig. 1 is a perspective view of a holder for jellies or the like showing my new design;
Fig. 2 is a top plan view of the same; and
Fig. 3 is an end view thereof.

I claim:

The ornamental design for a holder for jellies or the like substantially as shown.

HELEN BISHOP DENNIS.
